DESIGN.

O. HEINIGKE.

CARPET.

No. 15,992.

Patented Mar. 24, 1885.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 15,992, dated March 24, 1885.

Application filed January 14, 1885. Term of patent 3½ years.

To all whom it may concern:

Be it known that I, OTTO HEINIGKE, of New Utrecht, New York, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

15 The design consists of three open flower and leaf groups, A, B, and C.

The group A is shown in the center of the photograph in all its details. It consists of various large leaves loosely massed, as shown, 20 and small open flowers and blossom sprays. Its white lichen-like sprays below approach but do not blend with the dark sprays of the groups B and C, and above and on the right its dark sprays similarly approach the white 25 sprays of the group C.

The group B is shown at the upper and lower corners of the photograph on the right and at the center on the left. It consists of two groups of star-shaped flowers and leaves springing from an open-leaf group below, and 30 with blossom and lichen-like sprays on all sides.

The group C is shown at the left upper and lower parts of the photograph and at the right center. It consists of a small group of star-shaped flowers above springing from a larger group below of star-shaped flowers and large open leaves, and with blossom and lichen sprays on all sides.

I claim—

40 The design for a carpet, consisting of the groups A, B, and C, substantially as shown and described.

OTTO HEINIGKE.
